US0D1009442S

(12) United States Design Patent (10) Patent No.: US D1,009,442 S
(45) Date of Patent: * Jan. 2, 2024

(54) SHOE

(71) Applicant: NIKE, Inc., Beaverton, OR (US)

(72) Inventor: Jason G. Petrie, Portland, OR (US)

(73) Assignee: NIKE, Inc., Beaverton, OR (US)

() Term: 15 Years

(21) Appl. No.: 29/889,653

(22) Filed: Apr. 14, 2023

(51) LOC (14) Cl. 02-04

(52) U.S. Cl.

USPC D2/969

(58) Field of Classification Search

Primary Examiner — Jonathan J Han

(74) Attorney, Agent, or Firm — Banner & Witcoff, Ltd.

(57) CLAIM

The ornamental design for a shoe, as shown and described.

DESCRIPTION

FIG. 1 is a front perspective view of a shoe showing my new design;

FIG. 2 is a side view thereof;

FIG. 3 is a rear perspective view thereof;

FIG. 4 is an opposite side rear perspective view thereof;

FIG. 5 is an opposite side view thereof; and,

FIG. 6 is an opposite side front perspective view thereof. The broken lines and unshaded regions depicting the remainder of the shoe form no part of the claimed design.

1 Claim, 6 Drawing Sheets
